US0D1023143S

(12) **United States Design Patent** (10) Patent No.: **US D1,023,143 S**
(45) Date of Patent: ** Apr. 16, 2024

(54) **FRANKING MACHINE**

(71) Applicant: **Francotyp-Postalia GmbH**, Berlin
(DE)

(72) Inventor: **Wolfgang Muhl**, Hohen Neuendorf
(DE)

(73) Assignee: **Francotyp-Postalia GmbH**, Berlin
(DE)

(**) Term: **15 Years**

(21) Appl. No.: **35/516,051**

(22) Filed: **Dec. 7, 2022**

(80) **Hague Agreement Data**

Int. Filing Date: **Dec. 7, 2022**
Int. Reg. No.: **DM/226044**
Int. Reg. Date: **Dec. 7, 2022**
Int. Reg. Pub. Date: **Jan. 20, 2023**

(30) **Foreign Application Priority Data**

Jul. 5, 2022 (EM) 009079551-0001

(51) LOC (14) Cl. **18-02**
